US00D981705S

(12) United States Design Patent (10) Patent No.: US D981,705 S
Laemle et al. (45) Date of Patent: * Mar. 28, 2023

(54) KEY TAG

(71) Applicants: David Laemle, Katonah, NY (US);
Kristy MacNeal, Norwood, NJ (US)

(72) Inventors: David Laemle, Katonah, NY (US);
Kristy MacNeal, Norwood, NJ (US)

() Term: 15 Years

(21) Appl. No.: 29/817,289

(22) Filed: Nov. 30, 2021

(51) LOC (14) Cl. 03-01

(52) U.S. Cl.

USPC D3/207

(58) Field of Classification Search

USPC D3/207, 208, 211; D21/338, 350, 468

CPC Y10T 70/8676; Y10T 70/8703; Y10T

24/1379; Y10T 24/3902; Y10T 24/1397
